(57) **CLAIM**

The ornamental design for a movable rainwater collector, as shown and described.

DESCRIPTION

FIG. 1 is a top perspective view of a movable rainwater collector, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1 thereof; and,

FIG. 10 is an enlarged detail view of area 10 in FIG. 2. The thin broken lines in the drawings illustrate the portions of the movable rainwater collector, which form no part of the claimed design.

The thick broken lines representing stitching are part of the claimed design.

The dash-dot-dash broken lines encircling the enlarged views are for annotative purposes only and form no part of the claim thereof.
